(57) **CLAIM**

The ornamental design for a case for an electronic communications device or the like, as shown and described.

DESCRIPTION

FIG. 1 is a front, right-side, and top isometric view of a case for an electronic communications device or the like showing my new design.

FIG. 2 is a front view of the case of FIG. 1.

FIG. 3 is a rear view of the case of FIG. 1.

FIG. 4 is a left side view of the case of FIG. 1.

FIG. 5 is a right side view of the case of FIG. 1.

FIG. 6 is a top view of the case of FIG. 1; and,

FIG. 7 is a bottom view of the case of FIG. 1.

The dot-dash broken lines in the drawing figures form no part of the claimed design and represent the bounds of the claimed design. The dash-dash broken lines throughout the drawing figures form no part of the claimed design and depict portions of the case for an electronic communications device or the like that form no part of the claimed design.
